UNITED STATES PATENT OFFICE.

JAMES T. WARNER, OF DETROIT, MICHIGAN, ASSIGNOR TO WHITEHEAD AND KALES COMPANY INCORPORATED, OF RIVER ROUGE, MICHIGAN, A CORPORATION OF MICHIGAN.

PERMANENT MOLD.

Application filed June 13, 1927. Serial No. 198,469.

The invention relates generally to molds and more particularly to permanent molds adapted for use in forming vehicle wheel hubs.

5 The invention has as one of its primary objects to provide a mold of this character which is distinguished by its simplicity, which may be constructed economically, assembled with facility and operated with ease. An-
10 other object of the invention is to provide a mold of this character arranged to permit maximum production and economical pour-
ing of the castings. A further object of the invention resides in the provision of a vehicle
15 hub mold permitting a secure anchoring of the spokes in the hub.

The invention also contemplates numerous novel details of construction and has as its object to simplify, render more efficient, and
20 improve generally apparatus of this character.

In certain types of permanent molds now more or less universally employed a serious disadvantage has been commonly experienced
25 in the necessity of using a certain amount of sand for the cope and drag portions of the mold, thus retarding production and resulting in porous castings. In the present invention this disadvantage is more than compensated for by the novel construction of the
30 mold which in addition to having a permanent drag and side walls is formed with a permanent cope.

The above objects and the novel details of construction of the invention will be made more apparent as this description proceeds especially when considered in connection with the accompanying drawings wherein;

Figure 1 is a top plan view of the mold constructed in accordance with this invention;

Figure 2 is a sectional view taken substantially on the line 2—2 of Figure 1;

Figure 3 is a view similar to Figure 2 showing the parts in open position;

Figure 4 is a sectional view taken on the line 4—4 of Figure 3;

Figure 5 is a sectional view taken on the line 5—5 of Figure 3;

Figure 6 is a sectional view taken on the line 6—6 of Figure 2;

Figure 7 is a detail perspective view showing the centering means for the cope portion of the mold;

Figure 8 is a diagrammatic view showing the counterbalancing means; 55

Figure 9 is a sectional view taken on the line 9—9 of Figure 2 and

Figure 10 is a sectional view taken on the line 10—10 of Figure 2;

Figure 11 is a sectional view on the line 11—11 of Figure 1.

Referring now more particularly to the drawings wherein like reference characters indicate like parts it will be noted that there is illustrated a table or frame including an outer circular rim 10 supported by suitable uprights 11. Projecting upwardly from the rim 10 of the table are supporting legs 12, each formed with a slot 13 for receiving the angularly turned end 14 of a spoke 15. As shown the legs 12 are formed with upwardly extending projections 16 serving to accurately align the spokes 15 relative to the hub to be cast in the mold. For positioning the lower series of spokes preparatory to forming the hub a series of plates 17 are secured to the rim 10 at proper intervals and are formed with spaced projections 18 for receiving and accurately positioning the outer ends of the spokes 19, both series of spokes being alternated in a well known manner. 70

The outer rim 10 of the table is connected by means of the spokes 20 to an inner ring 21 formed with a plurality of circumferentially arranged embossed portions 22 apertured to receive bolts 23. Secured to the enlargements by means of the bolts 23 is a stripper plate 24 having a downwardly extending guide portion 24' formed with the aligned bearing portions 25 and 26 for receiving an operating shaft 27. Arranged for vertical movement within the guide portion 24' is a sleeve 25' cut away as indicated at 26' to provide clearance for the bearing portions and formed with an elongated slot 27' in the upper end thereof. Adjacent the opposite sides of this slot are the upwardly extending ears 28 apertured to receive the pin 29 carrying a connecting rod 30, which is operated by an eccentric 31 keyed to the operating shaft 27. 85

In order to insure a proper alignment of the sleeve 25 with respect to the mold, wear plates 32 are adjustably positioned between the sleeve and guide portion 24' of the stripper plate. Bolted or otherwise secured to the sleeve 25' is a stool plate 33 forming the bot- 90 95 100 105

tom wall of the mold and formed with a conical portion 34, which in one position of the stool plate engages a conical seat portion 35 formed in the upwardly and inwardly extending flange 36 of the table. The bottom surface 37 of the flange cooperating with a circumferential flange 38 formed on the stool plate for limiting the upward movement of the latter. The stool 33 is also formed with 10 a depending flange 39 arranged to seat upon the stripper plate 24 when the former is in its lowermost position.

To form the side walls of the mold a pair of swingingly mounted cheeks 40 are connected by means of the connecting rod 41 to a pair of vertical shafts 42 mounted on the table. Due to the fact that the cheeks 40 swing in a relatively large arc some means must be provided other than the uprights 12 for supporting the outer ends of the upper series of spokes. For accomplishing this result a ring 43 comprising three sections 44, 45 and 46 is provided. As shown in Figure 1 of the drawings the center segment 45 together with the inner ends of the segments 44 and 46 are mounted on top of the shafts 42, while the outer ends thereof are secured to certain of the upright members 12. For accurately positioning the spokes upon the ring the latter is formed with a recess 47 for receiving the inturned end of the spoke and is provided with the spaced projections 48 for preventing lateral movement of the spokes. For conveniently operating the cheeks 40 the handles 48' and operating lever 49 are provided. The latter being pivotally mounted on the table and having a portion extending beyond the pivotal connection and arranged to engage in a suitable recess 50 formed in the lower edge of the cheeks 40. Thus when the cheeks are in closed or operating position they may be initially separated from each other by manipulating the lever 49. For effectively holding the cheeks in operative position the arcuate shaped lever 51 is provided, one end of which is formed with an elongated slot 52 for the reception of a pin 33 attached to one of the connecting rods adjacent the connection 50 thereof with the cheek. The handle portion of the lever is formed with a cam portion 54 and a notch 55 positioned in the inner arcuate surface of the lever and arranged to engage a pin 56 extending upwardly from 55 the opposite connecting rod. In order to provide a tight seal between the two cheeks the lever 51 is formed with an enlarged portion 57 extending beyond the pivot pin 53 and formed with a longitudinally extending bore 58 within which a plunger 59 is reciprocably mounted. The plunger is formed with an enlarged head portion arranged to engage the pin 53 under the tension of a coil spring 60 which engages the enlarged head of the 65 plunger and is held in position by means of

a suitable plug 61. Thus it will be readily apparent that the foregoing arrangement compensates for any wear of the cheek engaging surfaces and the latter are yieldably held in firm engagement with each other.

Referring now to the upper or cope forming portion of the mold a pillar 62 is rigidly or non-rotatively mounted upon one of the uprights 12 by means of the bearing cap 63 and key 64. Sleeved upon the pillar 62 is a tubular member 65 having slots 66 and 67 arranged in diametrically opposite sides thereof, within which a rack bar 68 and a key 69 are respectively sectioned. Slidably mounted on said tubular member are spacing collars or bushings 70 having diametrically opposite slots 71 and 72 formed therein for receiving the rack bar and key respectively, and secured to these bushings by means of the screws 70' is the upper mold support 73. As shown particularly in Figures 2, 3 and 9 of the drawing this support is formed with a transverse slot adjacent the lower end thereof of which together with the cap 74 forms a housing 75 for a transversely extending shaft 76. The reduced portion 77 of the cap and the bearing portion 78 of the support 73 constituting a bearing for the shaft. Arranged within the housing and keyed to the shaft 76 is a gear 79 meshing with the rack bar 68 and operable to raise the support 73 upon rotation of the shaft 76, which is accomplished by means of the hand wheel 80 keyed to one end of the shaft. Secured to the opposite end of the shaft is a suitable clutch member 81 adapted to engage a co-operating clutch member 82 secured to one end of the housing and operable to lock the hand wheel from rotation. For normally holding the clutch members in engagement a coil spring 83 is provided. As shown, in Figure 9 this coil spring surrounds the forward end of the shaft 76 having one end abutting against the hand wheel and the opposite end engaging the housing. Thus when it is desired to move the support 73 it is necessary to exert an inward pressure on the hand wheel, whereupon the spring is compressed and the clutch members are disengaged. Suspended from and carried by the support 73 by means of the arm 84 is a segmental tubular guide member formed of two parts 85 and 86, the former being formed integral with the arm 84 and the latter being secured to the former by means of the bolts 87. As shown, the segmental tubular member is formed with a plurality, four in number, of radially inwardly extending projections 88 apertured to receive the pins 89. Pivoted secured to each of the projections 88 are the links 90 having elongated slots 91. Arranged within the tubular guide member and capable of movement relative thereto are a plurality of quadrants 92, the lower surfaces of which constitute the upper por-

tion of the mold. As shown each of these quadrants is formed with an outwardly extending projection 93 apertured to receive a pin 94 which in turn is received in the slots 91. Thus each of the quadrants are movable relative to one another and relative to the guide member. For holding the quadrants in operative position the segments 85 and 86 are formed with conical seat portions 94' and 95 arranged to contact with corresponding conical portions 96 and 97 formed upon each of the quadrants 92. As shown, the lower edges of the quadrants are formed with the slots 98 which cooperate with the upper portions of the cheeks to accurately position the inner edges of the upper series of spokes relative to the mold.

Assuming that the top mold is apparent in the position shown in Figure 2 and it is desired to raise the cope the operator disengages the locking clutch by exerting an inward pressure upon the hand wheel 80 and rotates the same in a clockwise direction causing the gear 79 and consequently the mold support to move upwardly upon the rack 68 and key 69. As evidenced from the above figure the segmental tubular guide member will also move upwardly and due to the slot and pin connection between the segmental guide member and quadrants the latter will remain stationary until the pins travel the full extent of the slots 91 in the links 90, whereupon the quadrants will be carried outwardly, due to the engagement thereof with the finished casting, and upwardly to the position shown in Figure 3. On the other hand when it is desired to lower the cope the segmental guide and quadrants are lowered as a unit until the latter contacts with the cheeks preventing further movement of the quadrants. Downward movement of the segmental guide member, however, is continued until the concial seat portions 94' and 95 engage the corresponding concial surface 96 and 97 on the quadrants, whereupon the latter are forced inwardly and downwardly to the position shown in Figure 2.

From the foregoing it will be readily apparent that inasmuch as the top portion of the mold is swingingly mounted with respect to the remaining parts of the mold some means must be provided for accurately centering the quadrants relative to the center strip and cheeks. For accomplishing this result a plate 99 is secured to the upper end of the pillar 62 and is formed with a projection 100 apertured to threadedly receive the bolt 101, one end of which engages a projection 102 on the sleeve 67.

While it is believed that the operation of the machine will be thoroughly understood from the foregoing description a brief outline thereof will be given. Assuming that the several parts of the mold are in open position and the spokes are properly arranged on the supports provided for this purpose the

center strip 33 is moved into position by the guide member 24 operatively connected to the eccentric 30 and operating shaft 27. The cheeks 40 are then swung and locked into closed position by means of the lever 51. A core 103 is then placed in a suitable recess 104 formed in the center strip for forming the usual central aperture in the hub. The operator then lowers the cope portion of the mold and inserts the hollow sprue 105, the lower end of which is sleeved over a portion of the core 103 and forms the flared portion 106 of the hub. A weight 107 pivotally mounted in the segmental guide member functions to hold the sprue in position. In practice metal is poured at one side only of the sprue allowing the gases formed to escape out the opposite side. An aperture 108 is provided in this latter side through which the excess metal may flow. After the pouring operation is completed and the casting chilled the stool plate is lowered, the cheeks swung to the position shown in Figure 3 and the cope raised by means of the handle wheel. This latter action is accentuated by the provision of a counter balancing weight 109.

From the foregoing it will be apparent that the herein described construction permits a maximum production of molding due primarily to the fact that the cope, drag and side walls of the mold are permanent and may be used to form numerous hubs. Moreover with the above arrangement a quick pouring is accomplished due to the fact that the casting may be removed from the mold immediately after chilling. While the invention has been shown and described in connection with a mold for forming wheel hubs it will be readily apparent that the invention is broader than this in its scope and may be employed with equal facility to form various other castings. Therefore reservation is made to make such changes in the details of construction as may come within the purview of the accompanying claims.

What I claim as my invention is:

1. In a permanent mold, the combination with a support, of a member carried by said support forming the base of the mold, a pair of swingingly mounted cheeks forming the side walls of the mold, and a cope forming portion reciprocably and swingingly mounted relative to said members.

2. In a permanent mold, the combination of means forming the bottom and side walls of a mold, and a cope forming portion comprising a plurality of universally movable segments adapted to cooperate with one another to form the top of the mold.

3. In a permanent mold, the combination with a support, of a member reciprocably and swingingly mounted upon said support, and a cope forming portion comprising a plurality of quadrants pivotally mounted upon said member.

4. In a permanent mold, the combination with a table, of members mounted upon said table forming the bottom and side walls of a mold, a pillar vertically mounted upon said table, a supporting member reciprocably and swingingly mounted upon said pillar, and a cope forming portion comprising a plurality of quadrants pivotally mounted upon said supporting member.
5. In a permanent mold, the combination with a table, of members mounted upon said table forming the bottom and side walls of the mold, a pillar vertically mounted upon said table, a supporting member reciprocably and swingingly mounted upon said pillar having a segmental tubular guide portion, and a cope forming portion comprising a plurality of quadrants universally mounted within said guide portion.
6. In a permanent mold, the combination with a table, of means associated with said table forming the bottom and side walls of the mold, a tubular supporting member reciprocably mounted upon said table, and a cope forming portion arranged within said tubular portion and capable of movement relative thereto.
7. In a permanent mold, the combination with a table, of means associated with said table forming the bottom and side walls of the mold, a reciprocably mounted tubular supporting member, a cope forming portion comprising a plurality of quadrants positioned within said supporting member, and a connection between each of said quadrants and tubular member permitting a universal movement of the former with respect to the latter.
8. In a permanent mold, the combination with a table, of means associated with said table forming the bottom and side walls of the mold, a pillar vertically mounted upon said table, an upper mold support having a tubular guide member reciprocably and swingingly mounted upon said pillar, a cope forming portion comprising a plurality of quadrants positioned within said supporting member, and means including a pair of slotted links connecting each of said quadrants with said tubular guide member.
9. In a permanent mold, the combination with a table, of means mounted upon said table forming the bottom and side walls of the mold, an upper mold support carried by said table having a tubular guide portion, a cope forming portion arranged within said tubular guide member having a conical surface adjacent one end thereof, and a conical seat portion upon said guide member engageable with the conical surface aforesaid to accurately position the cope and move the same into engagement with the side walls of the mold.
10. In a permanent mold, the combination with a table, of an upper mold support carried by said table having a tubular guide portion, a cope forming portion comprising a plurality of quadrants arranged within said tubular guide portion and formed with conical surfaces, and conical seat portions upon said guide member engageable with the conical surfaces aforesaid to accurately position the quadrants.
11. In a permanent mold, the combination with a table, of an upper mold support carried by said table having a tubular guide portion, a cope forming portion comprising a plurality of segments arranged within said tubular guide portion and formed with conical surfaces, links connecting each of said quadrants with the guide portion having elongated slots therein permitting a lateral and longitudinal movement of said quadrants relative to the guide portion, a conical seat formed in said tubular guide portion, and means for operating the latter to bring the conical seat into engagement with the conical surfaces upon the quadrants for accurately positioning the latter.
12. In a permanent mold, the combination with a support, of a stripper plate secured to said support, a guide member reciprocable within said stripper plate, a drag forming member secured to said reciprocable guide, and a wear plate adjustably positioned between the stripper plate and guide for accurately centering the drag forming member.
13. In a permanent mold, the combination with a table, of a cope forming portion and a support therefor comprising a pillar non-rotatively mounted upon said table, a member rotatively sleeved upon said pillar having diametrically opposed slots therein, a key secured in one of said slots, a rack bar secured in the other of said slots, bushings sleeved upon said member having slots receiving said key and rack bar, an upper mold support carrying said cope forming portion sleeved upon said bushings, and a gear arranged within said upper mold support and meshing with said rack for raising and lowering the cope forming portion.
14. In a permanent mold, the combination with a table, of a pillar non-rotatively mounted upon said table, a member rotatively sleeved upon said pillar, an upper mold support carried by said member and constituting the cope forming portion of a mold, and means upon said pillar adjustably engaging a projection on said member for accurately centering the cope forming portion.
15. In a permanent mold, the combination with a table, of a cope forming portion reciprocably and swingingly mounted upon said table, and adjustable means for limiting the swinging movement of the cope and accurately centering the same.
16. In a permanent mold, a support, means upon the support forming the bottom and side walls of a mold, means including a plurality of independently movable sections

adapted to cooperate with each other to form the top of the mold, and means for moving said sections as a unit into operative relation to the side walls of the mold.

5 17. In a molding apparatus, a support, a member reciprocably mounted upon the support, a plurality of independently movable members swingingly mounted upon the reciprocable member aforesaid and capable of longitudinal movement relative thereto, and means operable upon reciprocation of said member to move and hold said members into engagement with each other to form one wall of a mold.

10 18. In a permanent mold, a support, means upon the support forming the bottom and side walls of a mold, a tubular member reciprocably mounted upon the support, a plurality of members swingingly mounted within

20 said tubular member and capable of longitudinal movement relative thereto, and means upon said tubular member engageable with the said members to move and hold the same into engagement with each other and into

25 accurate registration with the side walls of the mold to form the top wall of the latter.

19. In a molding apparatus, a support, a plurality of independently movable elements adapted to cooperate with each other to form

30 one wall of a mold, and a member reciprocably mounted upon said support and engageable with the elements aforesaid to move the latter inwardly and hold the same into engagement with each other.

35 20. In a molding apparatus, a support, a tubular member reciprocably mounted upon the support and a plurality of segments disposed within said tubular member and operable upon movement of the latter in one direction to automatically move into engagement with each other to form one wall of a mold.

40 21. In a molding apparatus, a support, a member reciprocably mounted upon the support, a plurality of segments loosely pivotaly connected to said member, and means upon the said member operable upon movement of the latter in one direction to move and hold

the segments in operative engagement with each other to form one wall of a mold.

50 22. In a molding apparatus, a support, a member reciprocably mounted upon the support, a plurality of segments adapted to cooperate with one another to form one wall of a mold, and a connection between the segments aforesaid and reciprocable member operable upon movement of the latter in one direction to permit the segments to swing outwardly to clear the mold.

55 23. In a molding apparatus, a support, a tubular member reciprocably mounted upon the support, a plurality of segments arranged within said tubular member, and a slotted pivotal connection between the segments and tubular member aforesaid permitting a universal movement of the segments relative to said member.

60 24. In a molding apparatus, a support, a member reciprocably mounted upon the support, a plurality of segments loosely pivotally connected to said member having arcuate body portions adapted to cooperate with each other to form a channel for the substance to be poured, the arcuate body portions of said segments terminating in lateral portions 70 adapted to cooperate with each other to form one wall of a mold.

65 25. In a permanent mold, the combination with a table, of means upon said table forming the bottom and side walls of a mold, a tubular member reciprocably mounted upon said table, and a cope forming portion disposed within said tubular member and actuated thereby to move into and out of registration with the means aforesaid.

75 26. In a molding apparatus, a support, a member reciprocably mounted upon the support, a plurality of independently movable members swingingly mounted upon the reciprocable member aforesaid and adapted to cooperate with each other in one position of the reciprocable member to form one wall of a mold.

In testimony whereof I affix my signature.

JAMES T. WARNER.
